[57]**CLAIM**

The ornamental design for a paver restraint, as shown and described.

DESCRIPTION

FIG. 1 is a perspective view of a first embodiment of a paver restraint according to this invention.

FIG. 2 is a top elevational view thereof.

FIG. 3 is a front elevational view thereof.

FIG. 4 is a bottom view thereof.

FIG. 5 is a right side elevational view thereof. The left side elevational view being a mirror image thereof.

FIG. 6 is a rear view thereof.

FIG. 7 is a perspective view of a second embodiment of a paver restraint according to this invention.

FIG. 8 is a top elevational view thereof.

FIG. 9 is a front elevational view thereof.

FIG. 10 is a bottom view thereof; and,

FIG. 11 is a right side elevational view thereof. The left side elevational view being a mirror image thereof.

The rear view of the second embodiment is identical that of the first embodiment shown in FIG. 6.

The paver restraint is broken on the web to indicate indefinite length.
